UNITED STATES PATENT OFFICE.

HARRY KOVACH, OF TAYLOR SPRINGS, ILLINOIS.

RAIL-FASTENING MEANS.

1,258,228.

Specification of Letters Patent. Patented Mar. 5, 1918.

Application filed September 15, 1917. Serial No. 191,591.

To all whom it may concern:
Be it known that I, HARRY KOVACH, a citizen of the United States, residing at Taylor Springs, in the county of Montgomery and State of Illinois, have invented certain new and useful Improvements in Rail-Fastening Means; and I do hereby declare the following to be a full, clear, and exact description of the invention, such as will enable others skilled in the art to which it appertains to make and use the same.

This invention relates to new and useful improvements in rail fastening means and has for its primary object to generally improve and provide reliable and substantial fastening means that can be quickly and readily attached to a rail and spiked to the tie.

A further object of the invention is to provide a fastening means which will effectively prevent spreading of the rails and which is of comparatively simple and inexpensive construction.

With these and other objects in view as will appear as the description proceeds, the invention comprises the various novel features of construction and arrangement of parts as will be fully described hereinafter and afterward specifically claimed.

30 Referring to the drawings:

Figure 1 represents a perspective view of my improved rail fastening means,

Fig. 2 represents another perspective view of the fastening means,

35 Fig. 3 represents a perspective view showing the two sections of the fastening means partly separated,

Fig. 4 represents a fragmentary vertical sectional view through the connecting portions of the two sections, and

40 Fig. 5 represents a vertical transverse sectional view taken on a plane indicated by the line 5—5 on Fig. 4.

Similar characters of reference are used 45 to denote like parts throughout the following description and the accompanying drawings.

In order that the construction and operation of the invention may be readily comprehended, I have illustrated an approved embodiment thereof in the accompanying drawings, and will now proceed to fully describe the same in connection with said drawings, in which 1 indicates the 55 outer section and 2 the inner section of the rail fastening means.

The outer section is provided with an upstanding portion 3 adapted to overlie the base flange and bear against the web of the rail. This portion 3 is formed at opposite sides with flanges 4 which reinforce and brace the upstanding portion 3. A reinforcing rib 5 is arranged intermediate the flanges 4, the upper end of which is adapted to bear against the under side of the ball of the rail. The base 6 is extended laterally beneath and to one side of the rail base flange and carries a pair of spaced upstanding ears 7 having shoulders 8 adapted to rest against the inner edge of the rail base flange. The base 6 has an opening 9 between the ears 7 and the opposed side walls of the ears and opening converge downward as indicated by 10 in Fig. 5, while one end wall inclines inwardly and the other end wall inclines inwardly and outwardly to provide a substantially V-shaped wall.

A tapered tongue 12 is carried by the inner section 2 and is adapted to be fitted and rest within the opening 9 when the outer overlapping portion 13 rests over the rail base flange, the inner end of the base 6 and against the rail web. The tongue is also formed with a shoulder 14 adapted to fit against the inner edge of the rail base flange and serves in connection with the ears 7 to rigidly hold the rail in place.

Recesses 15 are formed in the under side of the overlapping portion 13 for the reception of the ears 7 and serve in conjunction with the tongue to prevent relative transverse movement of the two sections. The forward portion of the base 16 of the inner section is concaved as at 17 for the reception of the inner rounded end 18 of the base 6 when the sections are fitted together, and when said sections are so fitted, the lower edge 19 will rest beneath the rounded end 18 and serve to prevent the section from rising up at their connections. A rib 20 is carried by and reinforces the inner section.

Both of the outer and inner sections are provided with spike openings 21 so that they can be spiked to the tie after they have been coupled together with the rail 105 to rigidly and effectively hold the rail in position.

While I have illustrated and described with particularity only a single preferred form of my invention I do not desire to be limited to the exact structural details thus illustrated and described, but intend to

cover all forms and arrangements which fall within the scope of my invention in the appended claims.

What I claim as new, is:

- 5 1. Rail fastening means comprising an outer section having a base portion adapted to underlie the rail base flange and project laterally to one side, an upstanding portion carried by one end of the base portion
10 adapted to overlie the rail base flange and bear against the rail web, upstanding ears carried by the other end of the base portion adapted to rest against the rail base flange, said base portion having an opening therethrough between said ears, an inner section having an overlapping portion adapted to rest on the rail base flange and the inner end of the base portion of the outer section and against the rail web, said
15 overlapping portion having recesses adapted to receive said ears, a tongue carried by said overlapping portion adapted to lockingly fit within said base opening and means for securing said sections to the rail tie.
- 20 2. Rail fastening means comprising an outer section having a base portion adapted to underlie the rail base flange and project laterally and inwardly to one side, the inner end thereof being rounded, an upstanding portion integral with the outer end of said base portion adapted to embrace the rail base flange, upstanding ears carried by the inner end of said base portion adapted to rest against the rail base flange, said base portion having an opening therethrough between said ears, an inner section having an overlapping portion adapted to rest on the rail base flange and the inner end of the base portion of the outer section, said overlapping portion having recesses for the reception of said ears, a tongue integral with said inner section, said tongue being of a shape corresponding to said base opening to snugly and lockingly fit therein, and means for securing both inner and outer sections to the rail tie.
- 25 3. Rail fastening means comprising an outer section having a base portion adapted to underlie the rail base flange and project laterally and inwardly to one side, an upstanding portion integral with the outer end of said base portion adapted to embrace the rail base flange, upstanding ears carried by the inner end of said base portion adapted to rest against the rail base flange, said base portion having an opening therethrough between said ears, the side walls of said opening converging downwardly while one end wall inclines inwardly and downwardly and the other end wall inclines inwardly and outwardly to provide a substantially V-shaped wall, an inner section having an overlapping portion adapted to rest on the rail base flange and the inner end of the base portion of the outer section, said overlapping portion having recesses for the reception of said ears, a tongue integral with said inner section, said tongue being of a shape corresponding to said base opening to snugly and lockingly fit therein, and means for securing both inner and outer sections to the rail tie.

of the base portion of said inner section being concaved for the reception of the inner rounded end of the base portion of the outer section, a tongue integral with said inner section adapted to lockingly fit within said base opening, and means for securing each of said outer and inner sections to the rail tie.

3. Rail fastening means comprising an outer section having a base portion adapted to underlie the rail base flange and project laterally and inwardly to one side, an upstanding portion integral with the outer end of said base portion adapted to embrace the rail base flange, upstanding ears carried by the inner end of said base portion adapted to rest against the rail base flange, said base portion having an opening therethrough between said ears, the side walls of said opening converging downwardly while one end wall inclines inwardly and downwardly and the other end wall inclines inwardly and outwardly to provide a substantially V-shaped wall, an inner section having an overlapping portion adapted to rest on the rail base flange and the inner end of the base portion of the outer section, said overlapping portion having recesses for the reception of said ears, a tongue integral with said inner section, said tongue being of a shape corresponding to said base opening to snugly and lockingly fit therein, and means for securing both inner and outer sections to the rail tie.

In testimony whereof I have signed my name to this specification in the presence of two subscribing witnesses.

HARRY KOVACH.
